CHRISTIAN WILLIAM HAERMALZ, OF PROVIDENCE, RHODE ISLAND.

Letters Patent No. 85,815, dated January 12, 1869.

IMPROVED SWIVEL MIRROR-FRAME.

The Schedule referred to in these Letters Patent and making part of the same.

To all whom it may concern:

Be it known that I, CHRISTIAN WILLIAM HAERMALZ, of Providence, in the county of Providence, and State of Rhode Island, have invented a new and useful Improvement in Swivel Mirror-Frames; and I do hereby declare that the following is a full, clear, and exact description thereof, which will enable others skilled in the art to make and use the same, reference being had to the accompanying drawing, forming part of this specification.

The object of this invention is to provide mirror-frames having adjustable attachments connected thereto for suspending them in an adjustable manner.

It consists in providing the frames with a fixed axle, projecting preferably from one side, about the middle, and connecting thereto a bracket, for attachment to the wall, for suspending the glass, the connection being such that the glass may be oscillated either in a horizontal or vertical plane.

The drawing shows a side elevation of my improved apparatus, partly broken away.

A represents the frame of the glass, which may be made of any suitable material, but which I prefer to make of metal, provided with a fixed axle, B, which will be cast with the frame, when made of metal.

C represents a swivel, supported in an arm of the bracket, so as to be adjusted in a horizontal plane, and provided with a set-screw to hold it at any point.

To this swivel the axle B is connected by a horizontal opening through it, wherein the axle may oscillate in a vertical plane, and may be also secured by a set-screw.

By this arrangement the glass may be adjusted to any desired position.

The bracket and swivel may also be made of cast-metal, requiring only the labor of tapping the holes for the set-screws, to fit them for use.

My improved attachment may be manufactured together with the frame, and furnished to the trade already for use with them, at a very small advance of cost upon the frame.

Having thus described my invention,

What I claim as new, and desire to secure by Letters Patent, is—

The bracket, having the horizontal arm, the swivel C, adjustable vertically and horizontally in said arm by means of the set-screw, and the arm B of the glass-frame A, adjustable horizontally in the swivel by means of the set-screw, all arranged as described, for the purpose specified.

The above specification of my invention signed by me, this 29th day of June, 1868.

CHRISTIAN WILLIAM HAERMALZ.
